TITRATOR ELECTRODE PAIR

Conrad M. Jankowski, Medinah, Ill., assignor to Central Scientific Co., a corporation of Illinois

Application June 17, 1957, Serial No. 666,105

2 Claims. (Cl. 204—271)

This invention relates to an electrode construction in which the electrodes are mounted in pairs for ease of handling and connection.

In the prior art the electrode arrangements employed in titration equipment have been mounted and connected individually, and this has been an annoyance that not only encumbers the actual titration operations but frequently leads to improper connections and erroneous results. This is particularly true where a single titration apparatus is arranged for use in numerous different titration operations, each of which may involve a different electrode pair arrangement. The consequent frequent handling of the electrodes, which, incidentally, have heretofore been of fragile construction, has resulted in breakage and loss of the electrodes.

The principal object of the present invention is to provide a long-lived, low-cost, metallic electrode pair arrangement of a simple and rugged construction that is readily replaceable and that can withstand rough handling.

Another object is to provide such an arrangement that is chemically inert in the solutions in which it is immersed.

Other objects and advantages will become apparent during the course of the following description.

In the accompanying drawings forming a part of this specification and in which like numerals are employed to designate like parts throughout the same,

Fig. 1 is a side-sectional view through one constructional embodiment of the invention;

Fig. 2 is a top plan view of the embodiment of Fig. 1; and

Fig. 3 is a sectional view corresponding to Fig. 1 and illustrating a different constructional embodiment in accordance with the invention.

As pointed up briefly hereinabove, the various different titration operations frequently require their own electrode pair arrangements, and the present invention deals with an electrode construction that offers important general advantages that are common to all of the individualized constructions although the specific details may vary considerably from one construction to another. For example, Fig. 1 discloses the indicator electrode pair construction for a mercaptan titration while Fig. 3 discloses the generator electrode pair for a mercaptan titration.

It is proposed to employ these electrode constructions with a titration apparatus that includes a rigid, polarized mounting socket for receiving the connection terminals and the socket is preferably arranged to support the electrode pair at an appropriate point for immersion in a solution under test that will normally be confined in a suitable beaker. In the usual arrangement, separate sockets are provided for the generator electrode pair and the indicator electrode pair so that the individual electrodes of each pair and the pairs themselves may readily be mounted in a predetermined, fixed relationship within the solution.

Referring now to the mercaptan indicator pair of elec-

2

trodes shown in Figs. 1 and 2, a holder body 10 is employed which is, preferably, in the form of a cylindrical rod of machineable material that may be suitably drilled for receiving the various parts of the finished assembly.

5 As shown, the rod is formed with a pair of small-diameter cylindrical bores or drill holes 11 that open through the lower end of the rod to receive the metal electrodes 12, a socket or large-diameter drill hole 13 that opens through its upper end to receive a terminal cap 14 of 10 molded plastic insulating material that carries the necessary connection terminals 15, and a pair of enlarged intermediate bores 16 that connect the small bores 11 to the socket 13, with flexible, insulated lead wires 17 disposed in the larger bores 16 and establishing electrical 15 connections between the electrodes 12 and the connection terminals 15.

It is important to a long-lived electrode construction that the holder be of a material that is chemically inert and non-absorptive in the presence of the solutions in 20 which it is immersed. Furthermore, it should be resistant to mechanical shocks and should present a rigid body that will protect the parts mounted in it. Finally, and possibly of greatest importance, it must be readily capable of forming a liquid-tight seal with the electrodes 25 12 in order to prevent seepage into the holder body when its lower end is immersed in the test solutions. If these solutions should creep up the electrodes and contact the internal connections, internal short circuits may develop, or, in any case, the equipment will deteriorate rapidly. With this in mind, a white ceresin wax 18 is deposited in molten form in the intermediate bores 16 to further seal the holder against seepage. The wax is chemically inert in the presence of most solutions.

Polytetrafluoroethylene, more commonly known under 30 the trade name "Teflon," is a material that is admirably well-adapted to serve as the holder body.

In assembling the various parts of the electrode holder, it is preferred to first connect the electrodes 12 to the lead wires 17, and this is done by wrapping one or two turns of wire around the side of the electrode and soft-soldering the parts together. The electrodes are then pushed downwardly through the small bores 11 until they reach the position in which they are shown in Fig. 1, and bores 16 may then be filled with molten wax, which 40 is allowed to set. The lead wires are then soft-soldered to the terminals 15, and the cap 14 is pressed into the socket 13 until it abuts the internal locating shoulder 20. The cap is preferably arranged for a force-fit within the socket. In the illustrated form, the electrodes are merely wedged through the bores 11 for a force-fit, and it has been found that with a Teflon body, a substantially perfect seal results and prevents the solution from seeping into the holder. It will be noted that any such seepage must scale the combined lengths of the 50 bores 11 and 16 before any possibility of setting up an internal short circuit arises.

In the case of mercaptan indicator electrodes the anode may be of platinum and the cathode may be of gold, and in order to prevent incorrect connections, the holder 60 is, in effect, polarized by using a terminal cap of the type shown with an appropriate polarized receptacle. It will be noted that the usual third terminal post 21 (Fig. 2) is removed so that the cap can fit correctly into its associated polarized receptacle (not shown) in only one position.

Fig. 3 illustrates an electrode construction for use as the generator pair in a mercaptan titration in which case both the anode 25 and the cathode 26 may be of silver. The construction is generally identical to that of Fig. 1, 70 and corresponding parts are similarly numbered. The cathode 26, however, is shown threaded to illustrate an alternative construction that is made possible with the

use of a Teflon-like holder body. It has been found that it is possible to form a sharp thread on an electrode and then screw it into the cylindrical bores that are formed in the Teflon body for receiving the electrodes and achieve a vacuum-tight seal. This construction could have been employed in the Fig. 1 arrangement in place of the wedge-fit electrodes.

It is, of course, well known that the silver anode 25 of the generating pair of electrodes of Fig. 3 will be consumed with use and will require replacement, and according to the invention, therefore, the bore 11' is of a somewhat larger diameter than the bore 11 in order to receive an anode socket 27, the top end of which is drilled out axially to receive the bottom end of the lead wire 17, and the bottom end of which is formed with a tapped axial bore 28 in which the threaded end of the silver anode 25 is received. With this construction, the anode 25 may readily be replaced by a new one whenever conditions require. In the arrangement of Fig. 3, a washer 29 of Teflon is mounted in an appropriate socket at the bottom end of bore 11' to prevent the solution from eating away the anode socket 27.

In assembly, the socket 27 is first connected to the lead wire 17 and the parts are passed into the holder from the bottom until the socket is flush with the downwardly facing shoulder 30 that defines the socket for the washer 29. The cathode 26, however, is again entered downwardly through the bore 11 until the threaded portion comes into play, at which time the exposed lower end of cathode 26 serves as a suitable handle for threading the cathode into its ultimate position. The washer 29 is pressed over the threaded end of anode 25, which may then be screwed into place to bring the washer snug against the shoulder 30. While there may be some initial seepage of solution up the anode 25, it will not result in any serious deterioration of the anode socket 27 since the washer 29 prevents circulation of the solution to the socket and, hence, limits any such deterioration of the socket.

It will be apparent that the objects of the invention have been accomplished in that the Teflon body forms a liquid-tight seal with the electrodes to prevent seepage into the body. The body rigidly connects the various parts and is itself unbreakable and chemically inert in the various solutions to which it will be subjected.

It should be understood that the description of the preferred form of the invention is for the purpose of complying with Section 112, Title 35, of the U.S. Code and that the claims should be construed as broadly as prior art will permit.

I claim:

1. A titrator electrode pair construction for partial

immersion in solutions such as are employed in mercaptan and olefin titrations and comprising a one-piece body of polytetrafluoroethylene bar stock, said body having a pair of substantially straight, small-diameter drill holes opening through its lower end, one of said holes being larger than the other, and a substantially straight, large-diameter drill hole opening through the upper end of the body and communicating with both of the small-diameter holes at the upper ends thereof, a socket of precious metal mounted within the lower end of the larger of said small-diameter holes in force-fit engagement with integral portions of said body bordering and surrounding the same, said socket having a tapped bore opening axially through its lower end, a consumable electrode of the same material as said socket and having a threaded upper end engaged in the tapped bore thereof, a second precious metal electrode mounted within the other of said small-diameter holes in force-fit engagement with integral portions of said body bordering and surrounding the same, with said integral portions of said body surrounding said socket and said second electrode being under compression to conform to the surface configuration thereof in liquid-tight engagement therewith, said electrodes projecting from the lower end of said body, a cap of insulating material mounted in the said large-diameter hole and carrying a pair of external terminals, and wires totally within said body and connecting said terminals to said socket and said second electrode.

2. The electrode pair construction of claim 1 wherein said body, at its lower end, has a recess surrounding the lower end of the larger of said small-diameter drill holes to form an outwardly facing ring-like shoulder substantially flush with the lower end of said socket, and a washer of polytetrafluoroethylene is disposed in said recess in snug-fitting telescoping relation over said consumable electrode and in abutting engagement with said shoulder.
